UNITED STATES PATENT OFFICE.

FRANK J. KOZIK, OF EASTHAMPTON, MASSACHUSETTS

AUTOMATIC FLUSHING DEVICE.

1,213,886.

Specification of Letters Patent. Patented Jan. 30, 1917.

Application filed November 20, 1916. Serial No. 132,407.

To all whom it may concern:

Be it known that I, FRANK J. KOZIK, a citizen of the United States, residing at Easthampton, in the county of Hampshire and State of Massachusetts, have invented certain new and useful Improvements in Automatic Flushing Devices, of which the following is a specification.

This invention relates to certain new and useful improvements in automatic flushing devices.

The primary object of the invention is the provision of an automatic means serviceable in connection with water closets adapted for automatically tripping the flushing mechanism whenever desired, the arrangement being easy and inexpensive to manufacture and capable of installation upon water closets already installed.

20 A further object of the device is the arrangement of a foot controlled tripping means for the flush valve of a water closet whereby the mechanism is set by stepping upon an actuating member, the tripping operation taking place upon stepping off of such member.

With these general objects in view and others that will appear as the nature of the invention is better understood, the same consists in the novel construction, combination and arrangement of parts hereinafter more fully described, illustrated in the accompanying drawings, and then claimed.

In the drawing forming a part of this application and in which like designating characters refer to corresponding parts throughout the several views:—Figure 1 is a side elevation of a water closet provided with the present device, portions of the same and the supporting floor being shown in vertical section illustrating portions of the mechanism. Fig. 2 is a top plan view thereof. Fig. 3 is a longitudinal vertical sectional view through the flush tank and a portion of the device. Fig. 4 is an enlarged elevational view of the portion of the mechanism arranged within the flush tank, portions of the flushing mechanism being shown partially broken away, parts being illustrated by dotted lines in their tripped flushing operation. Fig. 5 is an enlarged vertical sectional view through the rear side of the flush tank and the lever and arm members of the device arranged in their normal positions, and, Fig. 6 is a similar view with the members arranged in their set positions.

The present foot-controlled flusher actuator is adaptable for different forms of water closet flushing mechanisms and the same is herein illustrated in connection with a 60 water closet comprising a bowl 10, flush tank 11 and connecting flushing pipe 12, the latter having an annular seat 13 within the tank 11 adapted for the closing reception of the ball valve 14. A stem 15 is secured to 65 the valve 14 having an angular link 16 pivoted thereto while a lifting rod 17 is provided having loose connections with the link 16, substantially as provided in the usual flush tank mechanism of a water closet. An 70 arm 18 is pivoted as at 19 to a bracket 20 within the tank 11 and extends through a guide member 21 upon the rear wall 22 of the tank, the said arm having the rod 17 pivoted to its free inner end as at 23.

A foot plate 24 preferably having a roughened upper face 25 is arranged within a receiving opening 26 in a frame 27 of the floor 28, the said plate 24 being preferably arranged directly forwardly of the bowl 10. 80 A depending central stem 29 is carried by the plate 24 freely slideable within the bore 30 of a block 31 carried by the lower partition 32 of the floor and an angular operating lever 33 pivoted to a bracket 34 upon 85 the partition 32 has a circular end 35 surrounding the stem 29. A helical spring 36 also surrounds the said stem between the lever end 35 and the block 31 whereby the plate 24 is resiliently maintained normally 90 elevated, the upward movement thereof being limited by lugs 37 carried by the plate 24 and normally engaging the lower face of the member 27. A tubular casing 38 is arranged upright on the floor 28 within which 95 a connecting rod 39 is freely arranged, the lower end of the said rod extending through an opening 40 in the floor 28 and having a pin and slot connection 41 with the adjacent end of the lever 33. 100

A trip bar 42 is pivoted to the bracket 20 as at 43 and extends through the adjacent sides 44 of the box 11 being pivotally connected as at 45 with the upper end of the rod 39 within the upper end of the casing 38. A hook 46 is pivoted as at 47 to the arm 18 and is resiliently held with its curved free end 48 arranged slightly spaced from the tank wall 22 by means of a spring 49 connecting the said wall with the said 110 hook. A spring 50 connects the lever 33 with the bracket 34 assisting the spring 36

in returning the lever 33 and the plate 24 to their normal positions as illustrated in Fig. 1 of the drawings.

The operation of the device will be apparent from the within detailed description thereof, it being seen that by stepping upon the plate 24, the springs 36 and 50 are tensioned while the pivot end 41 of the lever 33 is elevated carrying the rod 39 upwardly 10 and swinging the inner end of the bar 42 downwardly to a point within the hook 46 as illustrated in Fig. 6 and by dotted lines in Fig. 3, it being noted that the lower inner face 51 of the bar 42 is beveled, allowing 15 the same to engage the end 48 of the hook 46, swinging the hook upon its pivot 41 and passing inwardly thereof. The elements remain in this position as shown in Fig. 4 as long as the plate 24 is depressed, 20 but upon stepping off of the said plate and releasing the latter, the springs 36 and 50 return the lever 33, rod 39 and bar 42 to their normal positions, the engagement of the bar 18 with the hook 46 during the up- 25 ward movement of the said bar carrying the said hook and the arm 18 upwardly as illustrated by dotted lines in Fig. 4, thereby unseating the valve 14 and flushing the device by allowing the water 52 within the tank 11 30 to freely pass by the valve seat 13 through the pipe 12 and into the bowl 10.

A serviceable arrangement is provided whereby the flushing mechanism is automatically actuated by the feet of the operator positioned in the usual manner during the use 35 of the structure.

What I claim as new is:—

1. A device of the class described comprising in combination with a water closet having 40 a tank provided with a flusher pipe supplied with a ball valve, an arm pivoted in the said tank, loose link connections between the said arm and valve, a trip bar carried by the said tank, a resiliently mounted floor plate, an operating lever attached at one end to said plate, a rod connecting one end of the lever to one end of the bar, a hook pivoted to the said arm, a spring for maintaining the upper free end of the hook within 45

the path of travel of the said bar whereby 50 the bar in its upward movement is brought into tripping engagement with the said hook.

2. A device of the class described comprising in combination with a flush tank having a gravity seating flush valve, an arm pivoted 55 within the said tank, link connections between the said arm and valve, a limiting guide for the said arm, an upwardly-extending hook pivoted to the said arm, resilient connections between the said hook and the 60 adjacent side of the tank whereby the free end of the hook is normally arranged spaced from the said tank side, a trip bar for the said arm pivoted to the tank and having a lower beveled face adapted for frictional 65 moving engagement with the said hook during the downward movement thereof, and elevating means for the said bar adapted for upwardly moving the said arm upon an upward movement of the bar in the valve 70 unseating operation.

3. A device of the class described comprising in combination with a flush tank having a gravity seating flush valve, an arm pivoted 75 within the said tank, link connections between the said arm and valve, a limiting guide for the said arm, an upwardly-extending hook pivoted to the said arm, resilient connections between the said hook and the 80 adjacent side of the tank whereby the free end of the hook is normally arranged spaced from the said tank side, a trip bar for the said arm pivoted to the tank and having a lower beveled face adapted for frictional 85 moving engagement with the said hook during the downward movement thereof, elevating means for the said bar adapted for upwardly moving the said arm upon an upward movement of the bar in the valve unseating operation, the said means comprising 90 a normally resiliently elevated foot plate, a lever having one end operatively connected to the said plate, and a connecting rod between the opposite end of the said lever and the adjacent end of the said bar. 95

In testimony whereof I affix my signature.

FRANK J. KOZIK.
